FIG. 5.

UNITED STATES PATENT OFFICE.

ANGUS MACDONALD, OF MELROSE, MASSACHUSETTS.

HEADREST ATTACHMENT FOR BEDS.

1,353,537.

Specification of Letters Patent. Patented Sept. 21, 1920.

Application filed April 1, 1920. Serial No. 370,400.

To all whom it may concern:

Be it known that I, ANGUS MACDONALD, a citizen of the United States, residing at Melrose, in the county of Middlesex and 5 State of Massachusetts, have invented new and useful Improvements in Headrest Attachments for Beds, of which the following is a specification.

This invention relates to an ordinary bed 10 which includes a bed frame or supporting structure, and a spring frame supported by said structure and provided with a spring bottom, adapted to yieldingly sustain a mattress.

15 The invention has for its object to provide, as an attachment for an ordinary bed including the elements above mentioned, a rest adapted to support the head and shoulders of the occupant in an inclined position when this is desired, so that the occupant may lie either horizontally, or with the upper portion of the body more or less inclined, the attachment being applicable to the bed without change in, or modification of the latter.

The invention is embodied in the improvements which I will now proceed to describe and claim.

Of the accompanying drawings forming 30 a part of this specification,—

Figure 1 is a top plan view of a bed provided with an attachment embodying the invention.

Fig. 2 is a side view, portions of the bed 35 frame being broken away.

Fig. 3 is a section on line 3—3 of Fig. 1, portions being broken away.

Fig. 4 is a fragmentary sectional view, showing in section portions of the crank 40 shaft, and the nut and sleeve hereinafter described.

Fig. 5 is a section on line 5—5 of Fig. 1.

Fig. 6 is a section on line 6—6 of Fig. 2.

Fig. 7 is a section on line 7—7 of Fig. 3.

45 The same reference characters indicate the same parts in all of the figures.

In the drawings, 12, 12 represent the longitudinal side bars of a bed frame which may be of any suitable form and construction. There is nothing new in the construction of the frame here shown, and the bars 50 12 may be cylindrical rods or tubes, as usual,

and are suitably attached to the head portion 13 and foot portion 14 of the frame.

15 represents the usual frame which surrounds and is attached to the spring bed bottom 16, and is hereinafter called the spring frame. The frame 15 and bottom 16 embody nothing new with me, and may be of any suitable construction, the frame 60 being preferably composed of bars which are angular or L-shaped in cross section.

My improved attachment is designed for engagement with the transverse end bars of the spring frame 15, and with the side 65 bars 12 of the bed frame, without change or modification of said parts, and is constructed as next described. To the end bars of the spring frame 15 are secured angular brackets, each composed of an outer member 16, and an inner member 17, these members conforming to the said end bars as shown by Fig. 3, and being clamped thereon by bolts 18 having suitable heads and nuts. Said brackets project downwardly from 70 the spring frame at opposite ends of the latter, and have apertures in their lower portions, constituting bearings for a crank shaft, extending lengthwise of the bed and spring frames.

80 A portion of said shaft is formed by a preferably tubular section 19, journaled in one of the brackets, and provided with a crank 20. Another portion of the crank shaft is formed by a screw-threaded section 85 21, rigidly attached at one end to the section 19 by an internally threaded coupling sleeve 22, engaged with externally threaded meeting portions of the sections 19 and 21, as shown by Fig. 4, the threaded section 21 90 being provided with a reduced portion 23, (Fig. 3), journaled in the other bracket. The attachment includes a hinged portion support, adapted to sustain the head portion of a mattress, the main portion of which 95 rests on the spring bottom 16, and to be inclined at various angles, to incline the portion of the mattress which supports the head and shoulders of the occupant. Said support includes a rigid frame, which is 100 preferably a bent rod or bar having a transverse portion 25, and end portions or arms 26, and a spring filling or bottom 27 which may be of the same construction as the

spring bottom 16. The arms 26 are pivotally connected by bolts 28 with upstanding ears 29, which are rigidly supported by the side bars 12 of the bed frame. Said ears are 5 parts of inclined arms 30, which are curved at their upper ends to form shoulders 31 resting on the upper sides of the bars 12, as shown by Fig. 5. Curved clamping ears 32 are attached by bolts 33 to the arms 30, 10 said ears and arms partially embracing the bars 12.

The arms 30 are provided with horizontal shanks 34, which are attached by bolts 35 to a channeled transverse bar 36, the cross 15 sectional form of which is shown by Fig. 4. To the central portion of the bar 36 is attached by bolts 37, a sleeve or journal-box 38, in which the section 19 of the crank shaft is journaled, said sleeve being provided with 20 ears 39, (Fig. 5), through which the bolts 37 pass, and the bolts being provided with clamping nuts 40 bearing on opposite sides of said ears. The sleeve 38 constitutes an intermediate support of the crank shaft, 25 preventing the latter from springing between its end portions which are journaled in the bed frame brackets 16, 17, formed by the members.

With the threaded section 21 of the crank 30 shaft is engaged a nut 44, with which is connected by a neck 45 (Fig. 7), a split sleeve 46, having ears 47 adjustably connected by bolt 48. In the sleeve 46 is journaled a rock shaft 49, having arms 50 at its 35 opposite ends, to which arm extensions or struts 51 are secured by bolts 52. The outer ends of said struts are connected by pivot bolts 53 to the arms 26 of the head rest frame.

40 It will now be seen that rotation of the crank shaft changes the position of the nut 44 in such manner as to cause the struts 51 to vary the position of the head rest frame, and that said frame may be adjusted to 45 cause its spring bottom or filler 27 to lie either substantially in the plane of the spring bottom 16, or in a plane substantially at right angles to that of the bottom 16, or in planes variously inclined. It will also be 50 seen that the attachment may be installed by securing the end brackets formed by the members 16 and 17, to the end members of the spring frame, then securing the ears 29, and cross bar 36, to the side bars 12 of the 55 bed frame, then assembling the parts of the sectional crank shaft, after applying the nut 44 to the threaded section 21, the crank shaft being suitably mounted in its several bearings, then inserting the rock shaft 49 in the 60 split sleeve 46, and finally connecting the struts 51 with the ends of the rock shaft, and with the arms 26 of the head rest frame. The journal portion 23 of the crank shaft is provided with a reduced screw-threaded 65 tension 55, having a nut 56, said nut and the

adjacent end of the portion 21 bearing on opposite sides of the bracket in which the portion 23 is journaled, and preventing endwise movement of the crank shaft.

The rock shaft 49 is preferably a half 70 round or semi-cylindrical bar, inserted and adapted to turn freely in a tube 57, which is fixedly secured in the split sleeve 46.

I claim:

1. A head rest attachment, comprising a 75 pair of brackets adapted to be fixed to the end bars of a spring frame, and provided with downwardly projecting portions having crank shaft bearings, a head rest composed of a frame having a transverse portion, and arms, and a resilient filling supported by said frame, ears having means for engagement with the side bars of a bed frame, and hinged to the arms of the head rest frame, a sectional crank shaft journaled 80 in said bearings, and including a threaded section, a nut engaged with said threaded section and provided with a transverse sleeve, a rock shaft adapted to turn in said sleeve, and struts attached to said rock shaft 85 and pivoted to the arms of the head rest frame.

2. A head rest attachment, comprising a 90 pair of brackets adapted to be fixed to the end bars of a spring frame, and provided with downwardly projecting portions having crank shaft bearings, a head rest composed of a frame having a transverse portion, and arms, and a resilient filling supported by said frame, a transverse bar 95 located between said brackets and provided centrally with a crank shaft bearing sleeve in alignment with the bearings in said brackets, and with inclined arms at its opposite ends, formed to bear on the side bars of a bed frame, upstanding ears integral with said arms, and hinged to the arms of the head rest frame, clamping ears bolted to said arms, a sectional crank shaft journaled in 100 said bearings, and including a threaded section, a nut engaged with said threaded section and provided with a transverse sleeve, a rock shaft adapted to turn in said sleeve, and struts attached to said rock shaft and 105 pivoted to the arms of the said head rest frame.

3. A head rest attachment substantially as specified by claim 1, the said crank shaft being composed of a cylindrical section having a crank at one end, an externally 110 threaded section, alined with the cylindrical section and having a reduced journal portion fitted to turn in one of said brackets, and provided with means coöperating with the bracket to prevent endwise movement of the crank shaft, and coupling means detachably connecting the said sections.

4. A head rest attachment substantially as specified by claim 1, the said nut sleeve being split, and provided with compressing 115

means, and with a tube rigidly confined by the sleeve, and the said rock shaft being semi-cylindrical, adapted to turn in said tube, and provided with arms to which said

5 struts are bolted.

5. A head rest attachment substantially as specified by claim 2, the said crank shaft bearing sleeve being adjustable relatively to

said transverse bar to aline it with the bearings in said brackets, and provided with 10 means for positively securing it in its adjusted position.

In testimony whereof I have affixed my signature.

ANGUS MacDONALD.
